FIG. 1

FIG. 2

FIG. 3

FIG. 4

FIG. 1 is a front perspective view of a water cooler showing our new design;

FIG. 2 is a front elevational view thereof; and

FIG. 3 is an enlarged cross-sectional view of the water cooler taken substantially on the line 3—3 of FIG. 2.

The characteristic feature of our design resides in the recessed foot pedal.

The drain is shown in broken lines in FIG. 4 for illustrative purposes only.

We claim:

The ornamental design for a water cooler, substantially as shown and described.
